(57) **CLAIM**

The ornamental design for a single module device for covert alarm locator apparatus, as shown and described.

DESCRIPTION

FIG. 1 is a top perspective view of the invention.

FIG. 2 is a bottom perspective view of the invention.

FIG. 3 is a top plan view of the invention.

FIG. 4 is a bottom plan view of the invention.

FIG. 5 is a left or right side view of the invention; and,

FIG. 6 is a front or back elevation view of the invention.
